UNITED STATES PATENT OFFICE.

ERNEST G. H. SCHENCK, OF ORANGE, NEW JERSEY.

DESIGN FOR A CUT STONE.

SPECIFICATION forming part of Design No. 35,937, dated June 10, 1902.

Application filed April 7, 1902. Serial No. 101,856. Term of patent 14 years.

To all whom it may concern:

Be it known that I, ERNEST G. H. SCHENCK, a subject of the King of Belgium, residing at Orange, New Jersey, have invented and produced a new and original Design for a Cut Stone, of which the following is a specification, reference being had to the accompanying drawings, forming a part thereof.

In the drawings, Figure 1 is a plan view of a cut stone, showing a front cut in accordance with my design. Fig. 2 is a view of a cut stone, partly in perspective, illustrating in side elevation the same front shown in Fig. 1.

The leading and main feature of my design consists of a stone cut with a substantially circular outline in plan view (see Fig. 1) and having its front divided into spaces bounded by straight lines. A leading feature of the front of the stone cut in accordance with my design is a cross-shaped figure. This is shown in the drawings to be made up of a plurality

of five-sided figures *a*, meeting each other at the center, and surrounding it are a series of four-sided figures *b* and triangular figure *c*. Other series of four-sided figures *d* and *e* surround the same, and between the figures *e* are triangular facets *f*. As shown in Fig. 2, the front has a substantially rounded outline. A conventional bottom is shown in Fig. 2 in dotted lines. 30

Having described my design, what I claim as new is—

The design for a cut stone, substantially as shown and described.

In testimony whereof I have signed my name to this specification, at New York, N. Y., this 2d day of April, 1902.

ERNEST G. H. SCHENCK.
